UNITED STATES PATENT OFFICE.

JAMES E. KENNEDY, OF WASHINGTON, DISTRICT OF COLUMBIA.

GAS STOVE.

Application filed October 29, 1921. Serial No. 511,283.

To all whom it may concern:

Be it known that I, JAMES E. KENNEDY, a citizen of the United States of America, residing at Washington, in the District of Columbia, have invented certain new and useful Improvements in Gas Stoves, of which the following is a specification.

This invention relates to certain new and useful improvements in gas stoves and has particular reference to improved burner and grid constructions for gas stoves, the present application being a continuation, in part, of my copending application Serial Number 432,810 filed December 23, 1920, 15 upon gas stoves.

The primary object of the invention is to provide an improved burner construction for gas stoves whereby the same may be conveniently manufactured in considerable 20 quantity at a minimum expense with the resultant product extremely efficient and durable.

Another object of the invention is to provide a casing or hood for confining the heat 25 of the burner wherein improved means is provided for connecting said hood with the grid of a gas stove.

With the above general objects in view and others that will appear as the nature of 30 the invention is better understood, the invention consists in the novel form, combination and arrangement of parts herein-after more fully described in connection with the accompanying drawings, in which 35 like characters of reference indicate similar parts throughout the views.

In the drawings.

Figure 1 is a fragmentary vertical sectional view of a gas stove employing a 40 burner and a heat confining hood constructed in accordance with the present invention,

Figure 2 is an inverted plan view of the grid shown in Figure 1 with the heat confining hood removed,

Figure 3 is a top plan view of the burner shown in Figure 1,

Figure 4 is a fragmentary elevational view of the grid shown in Figure 2, and

Figure 5 is an enlarged fragmentary sectional view taken upon line V—V of Figure 1.

Referring more in detail to the several views, the present invention is shown in connection with a single burner plate stove embodying a frame 5 having an opening there-

in with the portion of the frame about said opening downwardly offset to provide a common form of ledge 6 for supporting the grid 7 which may be of cast metal with its 60 margin engaging the ledge 6 and having a central depending sleeve 8 defining a circular central opening through the grid, suitable radial fins 9 being formed on the upper surface of the grid and extending inwardly 65 toward the center of the latter opening as shown clearly in Figure 2 wherein alternate ones of the fins 9 are shorter than the remaining ones of the same.

In accordance with the present invention, 70 the grid 7 is provided at substantially uniformly spaced points externally of the sleeve portion 8 thereof with single lugs 10 and a pair of lugs 11, all of said lugs being separated from the horizontal or body portion 75 of the grid by means of kerfs or grooves as clearly shown at 12 in Figure 4 with respect to the lugs 11.

A cylindrical heat confining hood 13 preferably formed from a strip of sheet metal 80 with its ends connected by providing an interlocking internal fold 14, is attached at its upper margin to the sleeve portion 8 of the grid, and this hood is of sufficient height to depend below the sleeve portion 8 and surround the burner 15 as shown clearly in Figure 1. The tube or hood 13 is provided with cut-outs or notches in its lower edge at diametrically opposite points as clearly 85 illustrated at 16 and 17 respectively adapted 90 to receive the usual supporting lug 18 which is cast on the burner and the internally threaded inlet 19 which is also cast on the burner.

The present invention aims to provide a 95 simple and efficient means for securing the hood 13 upon the sleeve 8 and for this purpose the tubular hood 13 is preferably made of slightly greater internal diameter than the external diameter of said sleeve 8 with 100 its upper margin inturned as at 30 so as to slightly reduce the diameter of the hood at this point to such an extent as to allow the hood to be forcibly snapped past the lugs 10 and 11 until the inturned margin 20 105 engages behind said lugs in the grooves or kerfs 12. When thus positioned, the seam 14 is snugly positioned between the pair of lugs 11 and the hood is nearly permanently held onto the grid sleeve.

The burner 15 includes a hollow cast body 110 as clearly shown in Figure 1 including a plu-

rality of radial burner members 21 arranged in spaced relation and connected by integral outwardly inclined webs 22, the body being preferably open at the center so as to provide a cylindrical inner wall 23 which also connects the burner members 21, the webs 22 being extended at an outward inclination for the purpose of draining grease or the like as will be apparent from an inspection of Figure 1. The bottom edges of the side walls of the burner members 21 join with the edges of the webs 22, and being similarly inclined, provide comparatively large space between the bottom wall 24 and the webs 22 for the instantaneous passage of the gas to all of the burner members 21 from the inlet 19 with a minimum obstruction, which space gradually increases in size from the outer wall of the burner to the inner wall thereof. The burner members 21 are provided with V-shaped roof or top wall portions which merge with slightly inclined nearly vertical side walls, the lower edges of which connect with the webs 22 and by reason of this particular formation of the burner members practical drainage thereof is insured while the liability of the burner holes 25 becoming clogged is reduced to a minimum, said burner holes being provided in considerable quantity through the top walls of the burner members.

The body of the burner is preferably cast with the bottom open and with the lower margins of the inner and outer walls thereof set at an inclination as clearly seen in Figure 1 so that when the bottom wall 24 has its inner and outer margins flanged over on the lower margins of said walls as at 26, said bottom wall is effectively held to the body portion and with gas-tight joints so that leakage of the gas between the body and bottom members will not occur. In this way, the body portion may be cast without

the usual coring operation and the bottom member 24 may be constructed of sheet metal of the desired gage, stamped in disk form with a central opening.

It is believed that the construction and advantages of the present invention will be readily understood and appreciated by those skilled in the art from the foregoing description.

Minor changes may be made without departing from the spirit and scope of the invention as claimed.

What is claimed as new is:

1. In a gas stove, a grid including a horizontal plate portion with a central opening and having a depending sleeve bounding said opening and provided with external lugs separated from the horizontal plate portion by grooves, and a sheet metal tubular heat retaining hood depending from the tubular portion of the grid, said hood being telescoped onto said tubular portion of the grid and having an inturned upper margin engaging in said grooves.

2. In a gas stove, a grid including a horizontal plate portion with a central opening and having a depending sleeve bounding said opening and provided with external lugs separated from the horizontal plate portion by grooves, and a sheet metal tubular heat retaining hood depending from the tubular portion of the grid, said hood being telescoped onto said tubular portion of the grid and having an inturned upper margin engaging in said grooves, two of said lugs being arranged in adjacent spaced relation, and said hood comprising a formed strip of sheet metal with an interlocking seam joint between its ends snugly received between said two lugs.

In testimony whereof I affix my signature.

JAMES E. KENNEDY.
